(57) **CLAIM**

The ornamental design for a laser level, as shown and described.

DESCRIPTION

FIG. 1 is a perspective view of an embodiment of a laser level according to the invention.

FIG. 2 is a front elevational view of the embodiment.

FIG. 3 is a rear elevational view of the embodiment.

FIG. 4 is a left elevational view of the embodiment.

FIG. 5 is a right elevational view of the embodiment.

FIG. 6 is a top plan view of the embodiment; and,

FIG. 7 is a bottom plan view of the embodiment.

In the above drawings, any wording or numerals shown therein does not form a part of the invention.

1 Claim, 7 Drawing Sheets
